US0D1015161S

(12) **United States Design Patent** (10) Patent No.: **US D1,015,161 S**
 Gee, II et al. (45) Date of Patent: ** Feb. 20, 2024

(54) **CONTAINER**

(71) Applicant: **Vita-Mix Management Corporation**, Olmsted Township, OH (US)

(72) Inventors: **Jack W. Gee, II**, Willoughby, OH (US); **Matthew Dugan**, Medina, OH (US); **David J. Kolar**, Stow, OH (US)

(73) Assignee: **Vita-Mix Management Corporation**, Olmsted Township, OH (US)

(**) Term: **15 Years**

(21) Appl. No.: **29/802,704**

(22) Filed: **Aug. 6, 2021**

(51) LOC (14) Cl. **07-01**

(52) U.S. Cl.

USPC **D9/568**; D9/560; D7/530; D7/523

(58) **Field of Classification Search**

USPC D9/530, 531, 568, 528, 558, 574, 500, D9/537, 538, 539, 540, 541, 542, 543, D9/549, 550, 555, 569, 573, 434, 563, D9/499, 520; D7/509, 510, 533, 523, D7/530; D3/202

CPC B65D 21/0231; B65D 1/0246; B65D 2501/0081

(74) Attorney, Agent, or Firm — Dinsmore & Shohl LLP

(57) **CLAIM**

The ornamental design of a container, as shown and described.

DESCRIPTION

FIG. 1 is a perspective view of a container showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the figures are included for the purpose of illustrating portions of a container and form no part of the claimed design.

1 Claim, 6 Drawing Sheets
